US00D995118S

(12) **United States Design Patent** (10) **Patent No.:** **US D995,118 S**
Lee et al. (45) **Date of Patent:** **** Aug. 15, 2023**

(54) **BODY CLEANSING APPARATUS**

(71) Applicant: **LG ELECTRONICS INC.**, Seoul (KR)

(72) Inventors: **Gayeong Lee**, Seoul (KR); **Minji Seo**, Seoul (KR)

(73) Assignee: **LG ELECTRONICS INC.**, Seoul (KR)

(**) Term: **15 Years**

(21) Appl. No.: **29/801,918**

(22) Filed: **Aug. 2, 2021**

(30) **Foreign Application Priority Data**

Feb. 19, 2021 (KR) 30-2021-0008570

(57) **CLAIM**

The ornamental design for a body cleansing apparatus, as shown and described.

DESCRIPTION

FIG. 1 is a front, right side perspective view of a body cleansing apparatus showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an alternative perspective view, shown in a first environment of use;

FIG. 9 is another alternative perspective view, shown in a second environment of use;

FIG. 10 is another alternative perspective view, shown in a third environment of use;

FIG. 11 is another alternative perspective view, shown in a fourth environment of use; and,

FIG. 12 is another alternative perspective view, shown in a fifth environment of use.

The broken lines shown in the drawings depict portions of the article and form no part of the claimed design. The broken lines shown in FIGS. 8-12 depict environmental subject matter and form no part of the claimed design.

1 Claim, 12 Drawing Sheets
